UNITED STATES PATENT OFFICE.

VERNON ROYLE, OF PATERSON, NEW JERSEY.

JACQUARD-CARD REPEATER.

Application filed May 11, 1923. Serial No. 638,287.

This invention relates to an improvement in jacquard card repeaters and has for an object to provide such an apparatus in which the card cylinder may be vertically adjusted for the purpose of varying the pattern, while maintaining its face which is in operative relationship to the bank of selecting needles parallel with said needles. Another object consists in providing improved means for holding the card cylinder with the desired face in proper relationship to the bank of needles during the reciprocating movement of the operating carriage of the machine. A further object consists in providing certain improvements in the form, construction and arrangement of the several parts whereby the above named and other objects may be effectively attained. A practical embodiment of the invention is represented in the accompanying drawings, in which— Fig. 1 represents a detail front view, partly in section, showing the right hand part of the apparatus. Fig. 2 represents a view, complementary to Fig. 1, showing the left hand portion of the apparatus. Fig. 3 represents an enlarged detail side elevation, looking at the right hand end of the parts shown in Fig. 1. Fig. 4 represents a view similar to Fig. 3, with parts removed to show those behind. Fig. 5 represents a detail plan view of the locking plunger, and adjacent parts, for operating with one end of the card cylinder. Fig. 6 represents a detail side view showing one of the means for gauging the vertical adjustment of the core and cylinder. This invention is an improvement upon the apparatus shown and described in my United States Letters Patent No. 1,032,707, dated July 16, 1912, and is designed for use in connection with a machine such, for instance, as that shown in my United States Letters Patent No. 556,775, dated March 24, 1896. Consequently, the general construction and operation of the machine will not be herein shown or described, as it will be assumed that the same is familiar to those skilled in the art. The description here will be limited to those parts necessary to set forth the novel features and improvements that constitute my present invention.

The customary carriage which serves to reciprocate the card cylinder in operative relationship with the bank of selecting needles, is denoted by 1, and it is provided with suitable drive gears 2, 3 and connected actuating parts for imparting the usual step by step rotation to the card cylinder. This mechanism constitutes no part of my invention and will not, therefore, be further described.

At the front of the carriage 1 are mounted a pair of yokes 4 and 5, in each of which is swiveled an adjusting screw 6, 7, the said screws being provided with milled heads 8, 9 for manual operation.

On the said screws 6, 7 are threaded traveling nuts 10, 11 which are formed integral with supporting bearings 12, 13 for the core 14 of the cylinder 15.

As a result of this arrangement, it will be seen that the cylinder 15 may be adjusted vertically with respect to the bank of needles (not shown) so as to enable the operator to utilize different portions of the pattern cards.

The cylinder 15 is adjustably slidable longitudinally of the core 14, and may be secured at any selected position by the screw 16 which is fitted to enter any one of the holes 17 in the core 14. This enables the operator to select any portion, laterally considered, of the design on the cards.

A rod 18 is mounted in depending brackets 19, 20 that are supported by the bearings 12, 13, and is intended to receive in sliding engagement a supporting roller (not shown) over which the cards may be fed to the cylinder 15, in a well understood manner.

One end of the core 14, which is shown at the right in Fig. 1, has its journal 21 separate from it, but keyed thereto, as indicated at 22, and the said core is provided with a split sleeve 23 which surrounds the journal 21 and fits in the bearing 12 on the traveling nut 10. The extremity of the outer part of the sleeve 23 carries a pinion 24 that meshes with a gear 25 which is loosely mounted on a short shaft 26 carried in bores formed in the meeting ends of arms 27 and 28. Thus the shaft 26 also serves as a pin to unite the ends of the said arms 27, 28 in a pivoted joint. Arm 27 is fitted on a lateral projection of bearing 12 carried by traveling nut 10, while arm 28 is pivoted to the support of gear wheel 2 which constitutes part 110

of the actuating mechanism of the machine, as hereinbefore mentioned.

Another gear 29, which meshes with gear 2 of the machine operating mechanism, is 5 exactly like gear 25 and is freely mounted on the hub 30 of gear 25 so as to lie in abutment with the last named gear. Because of its free mounting, I choose to call the gear 29 a free gear. A clamping nut 31 is threaded 10 on the end of the hub 30 and abuts a collar 32 which is keyed for sliding movement on the said hub. This arrangement permits the nut 31 to be turned so as to firmly clamp the gear 29 to gear 25, through the intermediation of collar 32, and thereby cause the gear 29 to impart motion to gear 25 when the machine is in operation.

In order to prevent accidental movement of the card cylinder 15 such as to bring its operative face out of proper relationship to the bank of needles, I provide a notched disc 33 which is secured to the end of journal 21 by a pin 34, and to the pinion 24 by pins 33* (Fig. 3). This disc has four notches 35 which are intended to receive studs 36, 36 carried at the upper ends of arms 37, 37, which arms are pivoted at 38, 38 in a bracket 39 that is secured by a screw 40 to the under side of bearing 12. A retractile coil spring 41 has its ends connected to pins 42, 42 on the arms 37, 37 so as to normally urge them toward each other and thus retain the studs 36 in notches 35 in the disc 33. The pivoted ends of arms 37 have lateral projections toward each other which meet in the form of a ball and socket joint 43, and a lever 44 projects outwardly from the arm 37 which carries the ball of the joint 43, so that manual downward pressure on the said lever will cause the arms 37 to move apart against the tension of spring 41, thereby releasing their studs 36 from engagement with notches 35 in the disc 33. The provision of two arms with studs engaging two oppositely disposed notches provides a very positive and effective holding device for the purpose specified.

The object of the arrangement above described is to so arrange the mechanism that the card cylinder 15 may be vertically adjusted for the purpose of selecting a portion of the pattern on the card which is in operative position, while maintaining the operative face of the cylinder in parallelism with the bank of needles; and the parts operate in the following manner:

When the vertical adjustment is desired, it is only necessary to manually loosen clamping nut 31 and turn the milled heads 8, 9 of the screws 6, 7 in the desired direction, 60 which operation will cause the traveling nuts 10, 11 to move up or down, as the case may be, and thereby to carry core 14 and cylinder 15 to the predetermined vertical position. The arms 27 and 28 will yield 65 sufficiently about the shaft of drive gear 2

to permit this movement of the said parts, and, during this vertical adjustment (which may be assumed to be in an upward direction), the pinion 24 will cause gear 25, which is free on shaft 26, to rotate in an anti-clockwise direction, and thereby permit the core 14 and cylinder 15 to move upwardly about the axis of gear 2 as a pivot, without changing the parallel relationship of the operative face of the cylinder to the bank of needles, since the cylinder is yieldingly but firmly held in proper parallel position by the engagement of the arms 37 with the notched disc 33. After the desired vertical adjustment has been obtained, the clamping nut 31 is tightened down and the apparatus 70 may be set in operation in the regular way, during which operation, as is well understood, the notched disc 33 will be rotated with the cylinder and core in a step by step 75 manner, since the power of the drive of the machine is sufficient to force the studs 36 intermittently out of engagement with the notches 35. However, whenever the operation 80 of the apparatus is interrupted, the arms 37 will serve to hold the notched disc, and hence the core and cylinder, in proper 85 position, as above described.

The apparatus also includes a device for insuring that the operative face of the cylinder shall move against the bank of needles while lying in exact parallelism therewith during the reciprocating movement of the carriage 1, which device is shown in Fig. 5, and consists of a spring actuated plunger 45 90 that is mounted in a slide 46 carried on a bracket 47 which is secured to the main frame of the machine by cap screws 48. This plunger 45 has a tapered nose 49 which is designed to fit exactly in correspondingly 95 shaped notches 50 formed in a disc 51 that is fixed to the end of the core 14. As the carriage 1 is retracted in its reciprocatory movement (well understood in the art) so as to bring the face of the card cylinder 15 100 against the bank of needles, the nose 49 of the plunger 45 is forced tightly into a notch 50 in the disc 51 so that an exact fit between the two is obtained and the cylinder 15 held 105 in exactly parallel relationship with respect to the bank of needles while the operation of the cards thereupon is taking place. The construction and mode of operation of the device just described is substantially identical 110 with the corresponding device shown in Figs. 7 and 8 of my said prior Patent No. 1,032,707, and described in the specification thereof.

As a guide in the vertical adjustment of the core 14 and cylinder 15, I provide a calibrated scale 52 which is secured to the traveling nut 10 by screws 53, and has a slot that embraces a screw 54 fixed in the upper end of the yoke 4, which screw carries a double pointer 55 adapted to cooperate with the 115 120 125 130

calibrations on the scale 52. The said calibrations are preferably spaced so as to correspond with the lines of holes in the cards, in order that the operator may predetermine the vertical adjustment of the card cylinder, so as to utilize that portion of the pattern beginning at any desired line on the card. I also provide a scale, in which the calibrations are similarly spaced, on the side face of yoke 5, as clearly shown at 56 (Fig. 6). This scale is adapted to cooperate with a pointer 57 that is secured by a screw 58 on the traveling nut 11. This arrangement constitutes a guide for the operator in the vertical adjustment of the core and cylinder, which guide is located at the opposite side of the machine from the scale 52 and is so disposed as to be readily observed by the operator. It will be understood that various changes may be resorted to in the form, construction and arrangement of the several parts without departing from the spirit and scope of my invention; and hence, I do not intend to be limited to the details herein shown and described except as they may be included in the claims.

What I claim is:

1. An apparatus of the character described comprising, a card cylinder, means for intermittently rotating the same, and mechanism for holding the cylinder in various rotary positions, said mechanism including a device connected to the cylinder and locking elements engaging said device at a plurality of points so spaced that the locking elements grasp said device between them.
2. An apparatus of the character described comprising, a card cylinder, means for intermittently rotating the same, and mechanism for holding the cylinder in various rotary positions, said mechanism including a device connected to the cylinder and locking elements engaging said device at oppositely disposed points.
3. An apparatus of the character described comprising, a card cylinder, means for intermittently rotating the same, and mechanism for holding the cylinder in various rotary positions, said mechanism including a notched disc connected to the cylinder and locking elements engaging said notched disc at a plurality of points so spaced that the locking elements grasp said device between them.
4. An apparatus of the character described comprising, a card cylinder, means for intermittently rotating the same, and mechanism for holding the cylinder in various rotary positions, said mechanism including a notched disc connected to the cylinder and locking elements engaging said notched disc at oppositely disposed points.
5. An apparatus of the character described comprising, a card cylinder, means for intermittently rotating the same, and mechanism including a device connected to the cylinder and yielding arms engaging said device at a plurality of points.
6. An apparatus of the character described comprising, a card cylinder, means for intermittently rotating the same, and mechanism including a notched disc connected to the cylinder and yielding arms engaging said device at oppositely disposed points.
7. An apparatus of the character described comprising, a card cylinder, means for intermittently rotating the same, and mechanism including a notched disc connected to the cylinder and yielding arms engaging said device at a plurality of points.
8. An apparatus of the character described comprising, a card cylinder, means for intermittently rotating the same, and mechanism for holding the cylinder in various rotary positions, said mechanism including a notched disc connected to the cylinder and yielding arms engaging said notched disc at oppositely disposed points.
9. An apparatus of the character described comprising, a card cylinder, means for intermittently rotating the same, mechanism for holding the cylinder in various rotary positions, said mechanism including a device connected to the cylinder and yielding arms engaging said device at a plurality of points, and means for moving said arms out of engagement with the device comprising, projections extending laterally from the arms and mating in a movable joint, and a lever connected to one of said arms and one of said projections, whereby operation of the lever will directly move one of the arms and cause its projection to move the other arm.
10. An apparatus of the character described comprising, a card cylinder, means for intermittently rotating the same, mechanism for holding the cylinder in various rotary positions, said mechanism including a device connected to the cylinder and yielding arms engaging said device at oppositely disposed points, and means for moving said arms out of engagement with the device comprising, projections extending laterally from the arms and mating in a movable joint, and a lever connected to one of said arms and one of said projections, whereby operation of the lever will directly move one of the arms and cause its projection to move the other arm.
11. An apparatus of the character described comprising, a card cylinder, means for intermittently rotating the same, mechanism for holding the cylinder in various

BEST AVAILABLE COPY

- rotary positions, said mechanism including a notched disc connected to the cylinder and yielding arms engaging said notched disc at a plurality of points, and means for moving said arms out of engagement with the disc comprising, projections extending laterally from the arms and mating in a movable joint, and a lever connected to one of said arms and one of said projections, whereby operation of the lever will directly move one of the arms and cause its projection to move the other arm.
12. An apparatus of the character described comprising, a card cylinder, means for intermittently rotating the same, mechanism for holding the cylinder in various rotary positions, said mechanism including a notched disc connected to the cylinder and yielding arms engaging said notched disc at oppositely disposed points, and means for moving said arms out of engagement with the disc comprising, projections extending laterally from the arms and mating in a movable joint, and a lever connected to one of said arms and one of said projections, whereby operation of the lever will directly move one of the arms and cause its projection to move the other arm.
13. An apparatus of the character described comprising, a card cylinder having a plurality of faces, and means for vertically adjusting the same while maintaining its operative face in the same plane.
14. An apparatus of the character described comprising, a card cylinder, means for rotating the same, and means for vertically adjusting the cylinder, said rotating means including a member adapted to slip so as to permit the vertical adjustment of the cylinder to take place while maintaining its operative face in the same plane.
15. An apparatus of the character described comprising, a card cylinder, means for rotating the same, means for vertically adjusting the cylinder, said rotating means including a member adapted to slip so as to permit the vertical adjustment of the cylinder to take place while maintaining its operative face in the same plane, and means for locking said member against slipping.
16. An apparatus of the character described comprising, a card cylinder, a train of gears for rotating the same, and means for vertically adjusting the cylinder, said train of gears including one which is arranged to slip so as to permit the vertical adjustment of the cylinder to take place while maintaining its operative face in the same plane.
17. An apparatus of the character described comprising, a card cylinder, a train of gears for rotating the same, means for vertically adjusting the cylinder, said train of gears including one which is arranged to slip so as to permit the vertical adjustment of the cylinder to take place while maintaining its operative face in the same plane.
18. An apparatus of the character described comprising, a card cylinder, and means for actuating the same, said means including a drive gear, a gear connected to the cylinder, and an intermediate free gear.
19. An apparatus of the character described comprising, a card cylinder, means for actuating the same, said means including a drive gear, a gear connected to the cylinder, and an intermediate free gear, and means for locking said free gear in operative relationship with the other gears.
20. An apparatus of the character described comprising, a card cylinder, and means for actuating the same, said means including a drive gear, a gear connected to the cylinder, a third gear meshing with the last named gear, and a free gear intermediate the drive gear and third gear.
21. An apparatus of the character described comprising, a card cylinder, means for actuating the same, said means including a drive gear, a gear connected to the cylinder, a third gear meshing with the last named gear, and a free gear intermediate the drive gear and third gear, and means for locking said free gear in operative relationship with the drive gear and third gear.
22. An apparatus of the character described comprising, a card cylinder, and means for actuating the same, said means including a drive gear, a gear connected to the cylinder, and an intermediate free gear, said free gear being mounted in an arm supported on the cylinder bearing.
23. An apparatus of the character described comprising, a card cylinder, and means for actuating the same, said means including a drive gear, a gear connected to the cylinder, a third gear meshing with the last named gear, and a free gear intermediate the drive gear and third gear, said free gear and third gear being mounted in an arm supported on the cylinder bearing.
24. An apparatus of the character described comprising, a card cylinder, and means for actuating the same, said means including a drive gear, a gear connected to the cylinder, and an intermediate free gear, said free gear being mounted in a pair of arms, one arm being supported on the cylinder bearing and the other arm being supported on the drive gear bearing.
25. An apparatus of the character described comprising, a card cylinder, and means for actuating the same, said means including a drive gear, a gear connected to the cylinder, a third gear meshing with the last named gear, and a free gear intermediate the drive gear and third gear, said free gear and third gear being mounted in

- a pair of arms, one arm being supported on the cylinder bearing and the other arm being supported on the drive bearing.
26. An apparatus of the character described comprising, a card cylinder, and means for actuating the same, said means including a drive gear, a gear connected to the cylinder, and an intermediate free gear, said free gear being mounted in a pair of arms, one arm being supported on the cylinder bearing and the other arm being supported on the drive gear bearing, the shaft of said free gear constituting a pin for uniting said arms in a movable joint.
27. An apparatus of the character described comprising, a card cylinder, and means for actuating the same, said means including a drive gear, a gear connected to the cylinder, a third gear meshing with the last named gear, and a free gear intermediate the drive gear and third gear, said free gear and third gear being mounted in a pair of arms, one arm being supported on the cylinder bearing and the other arm being supported on the drive gear bearing, the shaft of said free and third gears constituting a pin for uniting said arms in a movable joint.
28. An apparatus of the character described comprising, a card cylinder, and means for actuating the same, said means including a drive gear, an arm mounted on the shaft of said drive gear, a gear con-
- nected to the cylinder, an arm mounted on the bearing of said gear, a shaft connecting the free ends of said arms to form a movable joint, a third gear provided with a projecting hub mounted on said last named shaft and meshing with the gear connected to the cylinder, a free gear mounted on said hub and meshing with the drive gear, and a clamping device threaded on the hub for bringing the free gear and third gear into driving engagement.
29. An apparatus of the character described comprising, a card cylinder, and means for actuating the same, said means including a drive gear, an arm mounted on the shaft of said drive gear, a gear connected to the cylinder, an arm mounted on the bearing of said gear, a shaft connecting the free ends of said arms to form a movable joint, a third gear provided with a projecting hub mounted on said last named shaft and meshing with the gear connected to the cylinder, a free gear mounted on said hub and meshing with the drive gear, a collar slidably but not rotatably mounted on said hub adjacent the free gear, and a clamping device threaded on said hub and adapted to force the collar against the free gear for bringing the free gear and third gear into driving engagement.

In testimony, that I claim the foregoing as my invention, I have signed my name this first day of May, 1923.

VERNON ROYLE.
